UNITED STATES PATENT OFFICE.

FREDERICK KEEES, OF MINNEAPOLIS, MINNESOTA.

DESIGN FOR A BADGE.

49,579.

Specification for Design.

Patented Aug. 29, 1916.

Application filed June 19, 1916. Serial No. 104,619. Term of patent 3½ years.

► *To all whom it may concern:*

Be it known that I, FREDERICK KEEES, a citizen of the United States, resident of Minneapolis, in the county of Hennepin and State of Minnesota, have invented a new, original, and ornamental Design for a Badge, of which the following is a specification, reference being had to the accompanying drawing, forming part thereof.

The figure is a plan view of a badge, showing my new design.

I claim:

The ornamental design for a badge, as shown.

FREDERICK KEEES.
